US00D957041S

(12) **United States Design Patent** (10) Patent No.: **US D957,041 S**
(45) Date of Patent: ** **Jul. 5, 2022**

(54) **ELECTRONIC CIGARETTE**

- (71) Applicant: **Altria Client Services LLC**,
Richmond, VA (US)
- (72) Inventor: **Mitchell Stone**, Staffordshire (GB)
- (73) Assignee: **Altria Client Services LLC**,
Richmond, VA (US)
- (**) Term: **15 Years**
- (21) Appl. No.: **29/756,808**
- (22) Filed: **Oct. 30, 2020**
